SCREW ANCHOR ADAPTER

Charles W. Kandle, Chicago, Ill.

Application October 4, 1944, Serial No. 557,180

2 Claims. (Cl. 287—20.1)

1

This invention relates to a screw anchor adapter for use in connecting the eye of a screw anchor to a power shaft for screwing the anchor into the ground.

Screw anchors have been employed for years for securing stay rods and cables for bracing telephone poles and the like. Such anchors have had various shapes, but all have a rigid eyelet at the upper end through which the cable or end of the stay rod is threaded. The lower end generally comprises a screw flight of one or two turns secured near the end of the central rod of the anchor. Such anchors are screwed into the earth on a slant directed toward the pole or object to be braced.

Heretofore it has been the practice to place such anchors manually although there has been available various power units that could be employed for this purpose both of the air motor and electric motor type.

The present invention is based upon the principle of utilizing a power drive for screwing anchors in place and for unscrewing the same when desired, and the invention has as its principal object the providing of an adapter for securing the end of the power shaft to the eyelet of the anchor and keeping the same in axial alignment at all times.

The invention is illustrated in the accompanying drawing in which:

Figure 1 is a perspective view illustrating the operation of placing a screw anchor in accordance with the present invention;

Fig. 2 is a front elevation of the adapter;

Fig. 3 is a side elevation of the adapter; and

Fig. 4 is a top plan view of the adapter.

In placing anchors according to the invention, the sod is first removed by manual shoveling and then the anchor 1 is positioned at the desired angle and a power unit 2 applied to screw the anchor into the ground.

The anchor 1 comprises a straight rod, usually of about three quarters of an inch in diameter, with its upper end bent to form a large eyelet 3, and having a short spiral screw flight 4 welded thereto near its lower end. The anchors are usually about five or six feet in length and are adapted to securely anchor guy wires and the like.

The power unit 2 comprises an electric motor having suitable reduction gearing for driving a power shaft 5. The casing for the unit has a pair of laterally extending handles 6 for manually holding the same during operation.

The power shaft 5 has an end female coupling member 7 with a square recess therein for receiving the square shank 8 of the adapter 9.

2

The adapter 9 comprises a casting having a clevis-shaped body 10 of substantial width and with aligned openings 11 and 12 through its opposite arms 13 and 14 for receiving a pin 15. The body 10 has the square shank 8 mounted centrally thereon and the lateral hole 16 extends through the shank for receiving a coupling pin 17 for securing the same to the coupling 7 of the power unit.

10 The body 10 of the adapter is adapted to receive the eyelet 3 of the anchor and prevent the same from turning relative to the adapter, and the pin 15 is adapted to pass through the eyelet and secure the same in place.

15 The arm 14 of the adapter extends downwardly a substantial distance beyond arm 13 and is provided with two spaced posts 18 between which the central rod of anchor 1 extends downwardly from eyelet 3 to hold the adapter in 20 alignment with the rod of the anchor.

In applying the adapter the eyelet 3 of the anchor is laid flatly against body 10 in the space between posts 18 and the end of arm 13 and this locates the rod of the anchor between posts 18. 25 Thereafter the eyelet 3 is moved upwardly between arms 13 and 14 until it registers with the aligned holes 11 and 12. The pin 15 is then inserted through the holes 11 and 12 and eyelet 3 to retain the latter in place. The pin 15 has a head 19, and a cotter pin 20 is secured in the opposite end to hold the pin in place.

The space between the arms 13 and 14 is only slightly larger than the eyelet 3 so that the arms 13 and 14 overlap and confine the eyelet against 35 turning relative to the adapter. The space between posts 18 and the end of arm 13 should be sufficient to substantially receive the eyelet 3 during insertion and removal.

The adapter has few parts and it rigidly secures the upper end of the anchor and turns the same with the motor shaft in either direction. It can be applied quickly and easily.

Various embodiment of the invention may be employed within the scope of the accompanying claims.

45 I claim:

1. An adapter for securing a screw anchor or the like formed of a substantially straight rod provided with an eyelet at the upper end thereof, which comprises a clevis-shaped member of substantial width adapted to closely confine the eyelet and having one side thereof extending downwardly beyond the other side for a substantial distance and beyond the position for the eyelet, a drive shank on the upper end of the member adapted to couple the same in driving

connection to a power shaft, means at the lower end of said extending side and spaced from the end of the shorter side a distance providing for the insertion of an eyelet between said sides for laterally confining the rod and holding the same in axial alignment with the adapter for turning, and a pin removably passing through the sides and adapted to pass through the eyelet when the latter is positioned between the sides.

2. An adapter comprising a clevis-shaped member of substantial width adapted to closely receive an eyelet having a projecting shank in the plane of the eyelet, said adapter having one arm extending downwardly beyond the other, posts on the lower end of said extended arm spaced apart to receive the shank of the eyelet and hold the same in axial alignment with the adapter for turning, said posts being spaced from the end of said shorter arm to provide for inser-

tion of the eyelet, and a pin removably passing through the arms and adapted to pass through the eyelet when the latter is positioned between the arms.
